IMPROVEMENT IN METERS FOR GAS AND LIQUIDS.

HOMER H. STUART, OF JAMAICA, NEW YORK.

Letters Patent No. 60,437, dated December 11, 1866.

The Schedule referred to in these Letters Patent and making part of the same.

TO ALL WHOM IT MAY CONCERN:

Be it known that I, HOMER H. STUART, of Jamaica, in the county of Queens, and State of New York, have invented a certain new and useful improvement in instruments for measuring the flow of fluids, commonly known as Gas or Water Meters; and I do hereby declare that the following is a full, clear, and exact description of the same, reference being had to the accompanying drawing making a part of this specification, and to the letters of reference marked thereon.

The object of my invention is to cause the rotation of a shaft or axle by means of the flow of a fluid, in such a manner that the quantity passing through the instrument will be recorded by an ordinary counter connected therewith.

To accomplish this purpose my invention consists in mounting upon an axle, that is inclosed in a case connected with the pipe through which passes the fluid to be measured a series of vanes that are extended to receive the impulse of the fluid entering the case, and remain extended while impelled by the fluid until it passes from the case, when they are folded or retracted until, by the rotation of the axle, they are again in succession presented to the action of the entering fluid.

To enable others skilled in the art to which it appertains to make and use my invention, I will proceed to describe its construction and operation with reference to the drawing.

Figure 1 is a section through the middle of a meter, represented as a water meter with the water passing through it in the direction of the arrows; and

Figure 2 is a plan of the same.

The vanes *a b c d* and *e* are hinged at their inner ends to a peculiarly shaped hub or shaft *f*. The vane *a* opposite the receiving pipe is just opening to the impulse of the water; the vane *b* is fully extended; that at *c* having passed the delivery pipe, is just beginning to be folded toward the shaft by coming in contact with the end of the circle *g* that fills the lower portion of the case; and the remaining vanes, *d* and *e*, are folded close against the hub. The vanes are successively extended on one side of the case to receive the impulse of the water to rotate the axle until they reach the delivery pipe, when they are folded towards the centre and are retained in a closed or collapsed position until they again reach the reception pipe, when they are again successively released and opened by their respective springs, *s*. It will thus be seen, on reference to the drawing, that the difference between the segments *x* and *y*, included by the vanes when extended and when collapsed, indicates the amount of water delivered by the passage of each vane.

Having thus described and illustrated the manner in which I prefer to make the instrument, it may here be remarked that the vanes need not be restricted to the number shown, and they may be made curved and furnished with packing on their peripheries, and fitted with butt-hinges extending along the angles of the hub, or otherwise, and the springs applied in a different manner or omitted. The form of the hub may also be varied without interfering with its function of sustaining the alternately extended and retracted vanes. The counter, which is represented in fig. 2 applied to the side of the instrument, may be of any of the ordinary kinds that are suitable for the purpose.

I claim as my invention, rotating the axle of a meter by vanes that are alternately extended and folded or retracted, substantially as described.

And I also claim, by this invention, to measure a fluid body by passing it transversely through a cylinder, or other circular vessel, containing vanes revolving, in said cylinder or circular vessel, in such a manner that the said vanes, while moving in the direction of the flowing body, are radii of a circle as large as the inner surface of the cylinder, and, while returning through the lower part of the cylinder to the point where the fluid is received, they are folded or retracted so as to be the radii of a circle smaller than the periphery of the cylinder.

Witnesses:

ANDREW STEWART.
